GEORGE KAUTZ, SR., OF ALBANY, NEW YORK, ASSIGNOR TO HULDAH M. KAUTZ, OF ALBANY, NEW YORK.

FRONT GEAR FOR WAGONS.

971,507.

Specification of Letters Patent. Patented Sept. 27, 1910.

Application filed August 27, 1909. Serial No. 514,949.

To all whom it may concern:

Be it known that I, GEORGE KAUTZ, Sr., a citizen of the United States, residing at Albany, in the county of Albany and State 5 of New York, have invented new and useful Improvements in Front Gear for Wagons, of which the following is a specification.

The invention appertains to wagons, more particularly to that class known as dumping-wagons, and the object is, generally, to improve upon and simplify devices of this nature and, specifically, to provide a novel construction of front running-gear, dispensing with one of the usual front wheels of the 15 wagon, and affording a structure whereby the single front wheel, used in my device, may be turned with a minimum of effort. In the usual construction of four-wheel wagon, the whipping of the wagon-tongue, 20 caused by one of the forward wheels striking an obstruction, results in the horse's breast and shoulders becoming sore and lame, frequently compelling the substitution of another horse, to the great detriment and loss 25 of the person using the wagon. By my peculiar construction of front running-gear and single wheel, this great objection is obviated.

Other minor and subsidiary objects, looking to the ultimate perfection of the device as an entirety, will appear as the specification proceeds and the different phases of the invention are exhibited.

In the accompanying drawing, I have exhibited a form of embodiment of my invention capable of carrying out the underlying principles; it being understood that the invention is susceptible of various modifications in detail, and all modifications as come 40 within the terms of the appended claims, constitute no departure from the spirit of the invention.

In the drawing: Figure 1 is a bottom plan view of the running-gear of the wagon; Fig. 45 2 is a section on the line 4—4, Fig. 1; Fig. 3 is a detail perspective view of certain parts of the running-gear, the annulus, or ring-plate, forming part of the running-gear, being omitted.

50 Referring, now, in detail to the drawing: A designates the wagon-bed, and a, a the two rear wheels of the wagon.

a', a' represent timbers, constituting part of the side framework of the wagon, and 55 which are hollowed out, as at a², on their in-

ner faces, for a purpose presently appearing; said timbers being duplicates of each other.

a³, a³ are transverse timbers, forming part of the framework of the wagon, and connecting the timbers a', a'. 60

Rigidly secured to the framework, as to the timbers a', a' and a³, a³, is an annulus or ring-plate a⁴.

a⁵, a⁵ represent wagon-hounds, carrying on their upper surfaces, medially of their 65 length, ears or shoulders a⁶, a⁶. Connecting said hounds, toward their extremities, and rigidly secured thereto, are two arc-plates a⁷, a⁷, working against the under surface of the annulus a⁴, as shown clearly in Fig. 1. 70

Rigidly secured to the hounds a⁵, a⁵ and disposed upon the upper surface of the shoulders a⁶, a⁶, are two straight plates a⁸, a⁸, the ends whereof bear upon the upper surface of the annulus a⁴, as shown in Fig. 2. 75

Disposed between the plates a⁸, a⁸ and the hounds a⁵, a⁵, and disposed on each side of the shoulders a⁶, a⁶, are anti-friction rollers a⁹, a⁹, a⁹, a⁹, which work against the inner 80 circumferential wall of the annulus or ring-member a⁴. In this instance, pins a¹⁰ passing through the plates a⁸, the rollers a⁹, and the hounds a⁵, constitute pivots for the rollers a⁹.

Mounted in bearings in the hounds a⁵, a⁵ 85 is an axle a¹¹, upon which is mounted the hub a¹² of a single front wheel a¹³. It will be understood, of course, that the wagon-tongues (not shown) are fastened to the front ends of the hounds a⁵, a⁵. 90

The operation of the device, and the coöperation of the parts, in turning the wagon, are as follows: The horse, in moving sidewise, will, through the wagon-tongues (not shown) fastened to the wagon-hounds a⁵, a⁵, exert a sidewise pull on the forward ends of said hounds; and said hounds, with their rigidly connected arc-plates a⁷, a⁷, and straight plates a⁸, a⁸, will swing, pivotally, in a horizontal plane, the wheel a¹³ turning 100 synchronously. During this movement, just described, the freely revoluble anti-friction rollers a⁹, working against the inner circumferential wall of the annulus, or ring-plate a⁴, insure that the front wheel a¹³ shall turn 105 with a minimum of effort, and that the hounds a⁵, a⁵ (and said connected plates) shall also swing, pivotally, with a maximum of ease. It will be noted, therefore, that the wagon-hounds a⁵, a⁵, with their rigidly 110

attached plates a^7 , a^7 , a^8 , a^8 are hung to swing upon the annulus or ring-plate a^4 , and that, as the rollers a^9 work against the inside periphery of the annulus, which is rigidly attached to the wagon-framework, the annulus thus governs and guides the hounds a^5 , a^5 and connected plates in their pivotal movement. The hollowed-out portions a^2 of the timbers a' insure that, during the swinging movement of the hounds a^5 , a^5 in turning the wagon, the ends of the plates a^8 , a^8 shall not jam against the inner faces of said timbers a' .

Having thus fully described my invention, what I claim as new and desire to secure by Letters-Patent is:

1. In a wagon, in combination with the front framework thereof, front running-gear, comprising a horizontally-disposed annulus rigidly secured to said framework, wagon-hounds disposed beneath said annulus, two arc-plates disposed on top of said wagon-hounds, extending transversely thereof, rigidly secured thereto, and bearing against the under surface of said annulus, two straight plates rigidly secured to said hounds and bearing, at their ends, upon the upper surface of said annulus, anti-friction rollers rotatably mounted between said straight plates and said hounds and bearing

against the inner circumferential wall of said annulus, and a single front wheel disposed between said hounds.

2. In a wagon, in combination with the front framework thereof, front running-gear, comprising a horizontally-disposed annulus rigidly secured to said framework, wagon-hounds disposed beneath said annulus, two arc-plates disposed on top of said wagon-hounds, extending transversely thereof, rigidly secured thereto, and bearing against the under surface of said annulus, shoulders carried on the upper surfaces and intermediate the length of said hounds, two straight plates rigidly secured to said hounds and disposed on top of said shoulders and bearing, at their ends, upon the upper surface of said annulus, anti-friction rollers rotatably mounted between said straight plates and said hounds and bearing against the inner circumferential wall of said annulus, and a single front wheel disposed between said hounds.

In testimony whereof, I affix my signature, in the presence of two subscribing witnesses.

GEORGE KAUTZ, Sr.
